UNITED STATES PATENT OFFICE.

CHARLES HALL, OF CHANGEWATER, NEW JERSEY, ASSIGNOR TO HIMSELF,
JACOB HILL, JR., AND VICTOR CASTNER, OF SAME PLACE.

ANIMAL-TRAP.

SPECIFICATION forming part of Letters Patent No. 295,634, dated March 25, 1884.

Application filed March 15, 1883. (No model.)

To all whom it may concern:

Be it known that I, CHARLES HALL, of Changewater, in the county of Warren and State of New Jersey, have invented a new and Improved Animal-Trap, of which the following is a full, clear, and exact description.

The object of my invention is to provide a new and improved trap for decapitating a number of animals successively.

10 The invention consists in the construction, combination, and arrangement of parts, as will be hereinafter fully described and claimed.

Reference is to be had to the accompanying drawings, forming a part of this specification, in which similar letters of reference indicate corresponding parts in all the figures.

Figure 1 is a longitudinal elevation of my improved trap. Fig. 2 is a plan view of the same. Fig. 3 is a detail plan view of the 20 releasing mechanism.

A powerful coil-spring, A, is attached to and surrounds a shaft, A', journaled in a board or frame, B, and a frame, B', attached to the same, which shaft A' is squared at one end, so as to 25 adapt it to receive a key for winding up the spring. On one end of the said shaft A' a ratchet-wheel, C, is rigidly mounted, and adjoining the ratchet-wheel an elbow-lever, D, is loosely mounted on the said shaft, on which 30 elbow-lever a pawl, E, is pivoted, which is pressed against the teeth of the ratchet-wheel C by a spring, E'. The bent end of a rod, F, is journaled in bearings G, secured to the base-plate H in such a manner that the said rod F 35 can swing in a vertical plane parallel with the plane of the coil-spring. The rod F passes loosely through the jaws of a U-shaped piece, J, pivoted to the end of the arm D' of the elbow-lever D, so that the said U-shaped piece 40 J can turn on the end of the said arm. To the free end of the rod F a knife or cutter, K, is attached, the cutting-edge of which is preferably serrated. On the base H a cross-shaped piece, L, is pivoted by a central pivot, around 45 which the said piece can turn, which piece L is so located that the end of the arm D' of the elbow-lever D can rest against one of the arms of the cross. A lever, M, provided with an arm, M', at an inclination to the lever, is pivoted at its bend to the base H in such a manner that the arms of the cross can rest against

the end of the arm M'. To the free end of the lever a plate, N, and two upwardly-projecting prongs, O, for holding the bait, are secured, which bait-holding end of the lever M is preferably contained in a separate compartment, P, of the trap. A lever, Q, is pivoted on the base H in such a manner that it can come in contact with the outer edge of the lever M. That end of the lever Q extending toward the 55 cross L is bent outward—that is, it is bent in the direction from the lever M, as is shown in Figs. 2 and 3.

The operation is as follows: The spring is coiled by means of a key, the plate N pressed 65 against the rear of the compartment P, and the bait is placed on the hooks O. When in this position the arm D' rests against one arm of the cross L, and is pressed against the same by the tension of the spring, and the adjoining arm of the cross L rests against the end of the arm M', and is pressed against the same. If a mouse nibbles at the bait, it pulls the free end of the lever M in the direction of the arrow a', and swings the inner end of the arm M' in the direction of the arrow b' sufficiently to release the end of that arm of the cross resting against the end of the arm M'. As the cross is released, the spring can swing the arm D' of the lever D in the direction of the arrow 70 c', and the inclination of the spring will cause a complete revolution of the shaft A'. Thereby the arm D' of the lever D will swing the rod F, carrying the knife K downward with great force, and the knife will decapitate the animal 75 nibbling at the bait, as the rod F is of such length that when it descends the knife K passes into the compartment P. As the arm D' passes by the bent end of the lever Q it presses the said bent end in the direction of 80 the arrow f', Fig. 3, and thereby causes the said lever Q to press the lever M in the inverse direction of the arrow a', so that the next arm of the cross L will strike against the end of the arm M' and be arrested. By this 85 time the shaft A' has completed its revolution, and the end of the arm D' of the lever D again rests against an arm of the cross L, as shown in Figs. 1 and 3. The trap will then be set for a second animal, and so on the trap continues decapitating animals and setting itself 90 until the spring A has been uncoiled.

The spring can be made of any size, so that it will decapitate a greater or less number of animals before it is uncoiled.

The trap can be made of different sizes for 5 mice, rats, opossums, foxes, and even for large animals—such as wolves and jackals.

In place of using a spring, A, a weight may be used which acts on the shaft A' by means of a chain or cord.

10 Having thus fully described my invention, I claim as new and desire to secure by Letters Patent—

15 1. In an animal-trap, the combination, with the spring A, of the shaft A', the elbow-lever D, the U-shaped piece J, the rod F, the knife K, the cross L, the lever M, provided with a bent arm, M', and devices for holding the bait on the free end of the lever M, substantially as herein shown and described, and for the 20 purpose set forth.

2. In an animal-trap, the combination, with

the spring A, of the shaft A', the elbow-lever D, the U-shaped piece J, the rod F, the knife K, the cross L, the lever M, provided with a bent arm, M', devices for holding the bait on 25 the free end of the lever M, and of the bent lever Q, adapted to act on the lever M, substantially as herein shown and described, and for the purpose set forth.

3. In an animal-trap, the combination, with 30 the spring A, of the shaft A', the ratchet-wheel C, the pawl E, the elbow-lever D, the pivoted U-shaped piece J, the swinging rod F, the knife K, the cross L, the lever M, provided with an arm, M', and the bent lever Q, substantially as herein shown and described, and for the 35 purpose set forth.

CHARLES HALL.
